DETECTOR FOR BLOOD ANALYSIS

James J. Sirago, 910 Enterprise, Inglewood, Calif. 90302,
and Edward B. Walton, 3129 Yale Ave., Marina Del
Rey, Calif. 90291

Filed Aug. 27, 1971, Ser. No. 175,797

Term of patent 14 years

Int. Cl. D24—02; D9—04

U.S. Cl. D16—1 R

FIG. 1.

FIG. 3.

FIG. 2.

FIG. 6.

FIG. 4.

FIG. 1 is a top plan view of a detector for blood analysis showing our new design;

FIG. 2 is a side elevational view as seen from the right of FIG. 1;

FIG. 3 is a side elevational view as seen from the top of FIG. 1;

FIG. 4 is a side elevational view as seen from the bottom of FIG. 1;

FIG. 5 is a bottom plan view thereof;

FIG. 6 is a side elevation as seen from the left of FIG. 1.

We claim:

The ornamental design of a detector for blood analysis, as shown.
